TELESCOPING POST

Joseph Oriold, Toronto, Ontario, Canada

Application November 14, 1946, Serial No. 709,680

6 Claims. (Cl. 248—161)

1

This invention relates to new and useful improvements in telescoping posts, with particular reference to telescoping posts such as are used in music-stands and microphones.

An object of this invention is to provide a more simplified and inexpensive telescoping device than those heretofore in use.

A further object of this invention is to provide a means for securely retaining the telescoping members in adjusted position which can be readily released so as to permit adjustment of the telescoping members.

A still further object of this invention is to provide a telescoping device which may be either completely opened or closed in a single manual movement.

According to this invention I provide a telescoping post comprising inner and outer telescoping members, the outer member being hollow and the inner member being longitudinally adjustable therein, a sleeve slidably mounted on the inner member having an inwardly projecting shoulder, a cramping ring loosely mounted on the inner member within the collar above the shoulder, and a projection mounted at the upper end of the outer member adapted to tilt the ring to cramp it on the inner member and prevent the inner member from telescoping within the outer member, the sleeve shoulder being adapted on moving the sleeve upwards to engage and straighten the cramping ring so as to permit the movement of the inner member relative to the outer member.

The novel features of this invention will hereinafter appear in detail in the description that follows and are illustrated, by way of example, in the accompanying drawings in which similar reference characters indicate corresponding parts and in which

Figure 1 is a side elevation;

Figure 2 is a fragmentary vertical section showing the cramping ring in the tilted position;

Figure 3 is a fragmentary vertical section showing the cramping ring in the straightened position; and

Figure 4 is a cross section on the line 4—4 in Fig. 2.

In the drawings a small rod or tube 1 telescopes within larger tube 2, which in turn telescopes within a still larger tube 3. Tube 3 telescopes within a still larger tube 4.

For convenience the invention is described with reference to the connection between tubes 3 and 4 although it will be understood that a similar connection is provided between the other tubes.

2

A sleeve 5 with longitudinal slits 6 therein is secured to the lower end of tube 3. Tube 3 may be constructed so that sleeve 5 is an integral part thereof. Sleeve 5 is wider than inner tube 3 and frictionally engages the inside walls of outer tube 4. Flat coil springs 7 secured at one end to the inside of sleeve 5, tend to spread sleeve 5 out still further. This provides enough friction so that inner tube 3 normally will not slide in outer tube 4 except by the application of additional weight or force. Instead of a flat coil spring a spiral coil spring may be employed.

An annular collar 8 having an upwardly projecting pin 9 is screwed on the upper end of outer tube 4. A sleeve 10 is slidably mounted on the lower end of inner tube 3 and extends over the upper end of tube 4. Sleeve 10 has an inwardly extending flange 11 at its lower end which engages the underside of collar 8 and acts as a stop to limit the upward sliding movement of sleeve 10. A cover 12 with a downwardly and inwardly sloping undersurface 13 is screwed on the upper end of sleeve 10. Cover 12 slidably embraces tube 3 and forms an inwardly extending flange which retains sleeve 10 spaced from tubes 3 and 4. A cramping ring 14 is loosely mounted on inner tube 3 within sleeve 10. Sleeve 10 is provided with an internal annular shoulder adapted to engage and support the cramping ring 14 when the sleeve is in raised position shown in Fig. 3.

The weight of sleeve 10 normally causes it to drop to the position shown in Figure 2 or it may be pushed into that position. Undersurface 13 of cover 12 engages cramping ring 14 against pin 9 which supports one edge of the ring tilting it to cramp it on inner tube 3, as shown in Figure 2, so as to prevent it telescoping within outer tube 4. The angle of the undersurface 13 of the cover 12 permits the tilting of the cramping ring. To change the relative positions of tubes 3 and 4, i. e. to lengthen or shorten the telescoped post, sleeve 10 is lifted manually, thereby engaging ring 14 on its shoulder 15 and lifting it to the straight or horizontal position, as shown in Figure 3. Tubes 3 and 4 can then be manually adjusted relative to one another and sleeve 10 then released, whereupon it will drop or may be pushed down to the position shown in Figure 2, causing ring 14 to tilt and lock the tubes in the new adjusted position. It is to be noted that when ring 14 is in the locking position while the post is prevented from being shortened it may be lengthened merely by pulling on tube 3, without any adjustment of sleeve 10.

Referring to Figure 1, inner tube 3 which telescopes within outer tube 4 serves as the outer

tube for inner tube 2. Inner tube 2, in turn, serves as the outer tube for inner tube 1. Each successive pair of inner and outer members has an identical locking device associated therewith as hereinbefore described with respect to tubes 3 and 4. Thus sleeve 16 is associated with tubes 2 and 3, and sleeve 17 is associated with tubes 1 and 2.

To completely telescope the post shown in Figure 1, tube 1 is grasped in one hand and the other hand is employed to push sleeve 10 towards tube 1. As sleeve 10 is pushed upwards it first straightens cramping ring 14 so as to permit tube 3 to telescope within tube 4. At the end of this telescoping movement cover 12 engages the lower end of sleeve 16 and moves it upwards to telescope tubes 2 and 3. Similarly, in turn, sleeve 16 acts as sleeve 17, thereby resulting in the complete telescoping of the post in a single manual movement.

It is thought that the construction and use of the invention will be apparent from the above description of the various parts and their purpose. It is to be understood that the form of the invention herewith shown and described, is to be taken as a preferred example of the same, and that various changes in the shape, size and arrangement of parts may be resorted to, without departing from the spirit of the invention or the scope of the subjoined claims.

What I claim as my invention is:

1. In a telescoping post, inner and outer telescoping members, the outer member being hollow and the inner member being longitudinally adjustable therein, a sleeve slidably mounted on the inner member having an inwardly projecting shoulder, a cramping ring loosely mounted on the inner member within the sleeve above the shoulder, and a projection mounted at the upper end of the outer member adapted to tilt the ring to cramp it on the inner member and prevent the inner member from telescoping within the outer member, the sleeve shoulder being adapted on moving the sleeve upwards to engage and straighten the cramping ring so as to permit the movement of the inner member relative to the outer member.

2. In a telescoping post, inner and outer telescoping members, the outer member being hollow and the inner member being longitudinally adjustable therein, a sleeve slidably mounted on the inner member extending over the outer member and having an inwardly projecting shoulder, a cramping ring loosely mounted on the inner member within the sleeve above the shoulder, a projection mounted at the upper end of the outer member adapted to tilt the ring to cramp it on the inner member and prevent the inner member from telescoping within the outer member, the sleeve shoulder being adapted on moving the sleeve upwards to engage and straighten the cramping ring so as to permit the movement of the inner member relative to the outer member, and stop means mounted at the upper end of the outer member and at the lower end of the sleeve adapted to limit the upward movement of the sleeve.

3. In a telescoping post, inner and outer telescoping members, the outer member being hollow and the inner member being longitudinally adjustable therein, a sleeve slidably mounted on the inner member having an inwardly projecting shoulder, a cramping ring loosely mounted on the inner member within the sleeve above the shoulder, a collar mounted on the outer member adja-

cent its upper end having a pin extending upwards therefrom, the pin being adapted to tilt the ring to cramp it on the inner member and prevent the inner member from telescoping within the outer member, the sleeve shoulder being adapted on moving the sleeve upwards to engage and straighten the cramping ring so as to permit the movement of the inner member relative to the outer member.

4. In a telescoping post, inner and outer telescoping members, the outer member being hollow and the inner member being longitudinally adjustable therein, a sleeve slidably mounted on the inner member extending over the outer member and having an inwardly projecting shoulder, a cramping ring loosely mounted on the inner member within the sleeve above the shoulder, a collar mounted on the outer member adjacent its upper end having a pin extending upwards therefrom, the collar being positioned within the sleeve below the shoulder and the pin being adapted to tilt the ring to cramp it on the inner member and prevent the inner member from telescoping within the outer member, the sleeve shoulder being adapted on moving the sleeve upwards to engage and straighten the cramping ring so as to permit the movement of the inner member relative to the outer member, and stop means adjacent the lower end of the sleeve adapted to engage the collar to limit the upward movement of the sleeve.

5. In a telescoping post, inner and outer telescoping members, the outer member being hollow and the inner member being longitudinally adjustable therein, a sleeve slidably mounted on the inner member extending over the outer member, the sleeve having an inwardly projecting shoulder and an inwardly extending flange having a downwardly and inwardly sloping undersurface, the flange embracing the inner member and retaining the sleeve spaced from the members, a cramping ring loosely mounted on the inner member within the sleeve above the shoulder and below said flange, a collar mounted on the outer member adjacent its upper end having a pin extending upwards therefrom, the collar being positioned within the sleeve, the sloping undersurface being adapted to engage the cramping ring against the pin to tilt the ring to cramp it on the inner member and prevent the inner member from telescoping within the outer member, the sleeve shoulder being adapted on moving the sleeve upwards to engage and straighten the cramping ring so as to permit the movement of the inner member relative to the outer member, and stop means adjacent the lower end of the sleeve adapted to engage the collar to limit the upward movement of the sleeve.

6. In a telescoping post, a plurality of hollow telescoping members of progressively increasing size forming successive pairs of inner and outer members in which the outer member of one pair forms the inner member for the next pair and in which the inner member is longitudinally adjustable within the outer member, each pair having a sleeve slidably mounted on the inner member extending over the outer member and having an inwardly projecting shoulder, a cramping ring loosely mounted on each inner member within each sleeve above the shoulder, a collar mounted on each outer member adjacent its upper end having a projection extending upwards therefrom, each collar being positioned within a sleeve and the projection being adapted to tilt the ring to cramp it on the inner member and prevent the

inner member from telescoping within the outer member, the sleeve shoulder being adapted on moving the sleeve upwards to engage and straighten the cramping ring so as to permit the movement of the inner member relative to the outer member, and stop means adjacent the lower end of the sleeve adapted to engage the collar to limit the upward movement of the sleeve,

the upper end of each sleeve being adapted when the device is being shortened to engage the lower end of the sleeve above it so as to move it upwards and permit the shortening of the pair of inner and outer telescoping members with which the latter sleeve is associated.

JOSEPH ORIOLD.
